ROLLING MILL HOUSING AND METHOD OF
CONSTRUCTING THE SAMEFlorence C. Biggert, Jr., Crafton, Pa., assignor to
United Engineering & Foundry Company, Pitts-
burgh, Pa., a corporation of Pennsylvania

Application January 13, 1933, Serial No. 651,523

5 Claims. (Cl. 29—148)

- This invention relates to rolling mills, and more particularly to a roll housing construction and method of constructing the same for such mills, and especially mills of relatively large sizes.
- With the advances which have been made in the art of metal rolling in the past couple of decades, and particularly in the rolling of relatively thin sheets and plates, mills of continually increasing sizes have been developed for rolling sheets and plates of correspondingly increasing widths. With the development of these larger sized mills, the problems involved in their construction have become more and more complex. Among these problems, one of the most difficult is that of eliminating what is known as stretching in the roll housings. This stretching is produced by the forces exerted upon these housings by the passing of the metal through the mill rolls, and is due to the elasticity of the metal out of which the housings are cast. The deleterious effect of this stretching is that it results in the production of sheets of varying thickness or, in other words, in inaccurate rolling, and frequently is the cause of sheets being rolled having insufficient uniformity of thickness to come within the tolerance normally permitted. In addition, this stretching frequently deforms these housings to such an extent as to cause them to subject the bearing blocks of the rolls, as well as the rolls themselves, to such strains as to cause their failure.
- To minimize this stretching of the housings, the usual practice is to increase the area or cross section of the housings to such an extent that they are capable of maintaining the stretching within tolerable limits. Such practice, however, in mills of exceedingly large sizes, for instance, mills capable of rolling sheets in widths of 84 inches and wider, gives rise to an exceedingly difficult problem of construction, as it necessitates these housings having such tremendous sizes that it is almost impossible to cast them in a feasible way. This latter problem will be more fully appreciated when it is considered that the castings for such housings run into weights varying from 250,000 to 400,000 pounds.
- It is an object of this invention to overcome these difficulties through the provision of a multiple part assembled housing which in addition to minimizing the aforementioned construction difficulties provides for a more efficient utilization of the metal employed in such a way that the stretching action produced by the rolling forces is materially reduced for a given size of housing section.
- These and other objects, as well as the various other novel features and advantages of the invention, become apparent when the following detailed description is read in conjunction with the accompanying drawings, of which Fig. 1 is an end view of a rolling mill showing a roll housing embodying the invention, the roll and screw-down assembly thereof being shown in dotted lines; Fig. 2 a side elevational view of the inner housing section or link; Fig. 3 a similar view of the outer housing section shown in Fig. 1 before the two are assembled, the latter section being shown in full lines as cast when cool, and in dotted lines (slightly exaggerated) as expanded for assembly; Fig. 4 a schematic force diagram of a mill housing comprising a single casting; and Fig. 5 a similar illustration of a mill housing constructed according to Fig. 1.
- Referring in detail to the drawings, the roll housing therein illustrated comprises an oblong link-like section 1, and a somewhat similar inner link section 2, which latter is rigidly fitted in the opening of the outer section. In each mill two of these built-up housings are employed, being joined together at their upper ends by upper cross beams not shown and at their lower ends by lower cross beams 4. For rigidity of construction, these lower cross beams are reinforced by a plurality of spaced tie plates 5. In the latter plates the base portions of the cross beams 4, which, in the present instance, are made in the form of an inverted T, are fitted, being seated in grooves 6 cut in the plates, and held against movement therein, as well as against the sides of the housing by wedges 7, which are forced between the outer edges of the tie plates and a tapered shoulder 8 forming the outer edge of the grooves 6.
- For receiving the usual roll assembly, which is designated generally by the numeral 9, the inner section 2 of the housing is provided with window-forming openings 10, and for adjusting the rolls of this assembly the usual screw-down assembly 11 is mounted on the top of the housing in the customary fashion to operate the adjusting screws 12. Inasmuch as these latter parts constitute no part of the present invention, they are, for clarity, illustrated in the drawings in dotted lines and referred to here only in a general way.
- According to this invention, in order to efficiently utilize the metal comprising the side walls of the roll housing and to also simplify the manufacture of the housing, the housing is cast in two link-like parts. These parts, as referred to above, comprise an outer link 1 and an inner link 2 which are cast separately, thereby making it possible to produce, with equivalent casting difficult-

ties, a housing having substantially twice the size of that which may be produced if the whole housing were to be cast in a single piece. In casting these parts the outer link is provided with an 5 oblong inner opening 14 which is rounded at its two ends on the radius of a circle and the sides of this opening, which are parallel, are made tangent to the circumference of the end circles. The inner link, in turn, is provided with an outer contour or peripheral surface which is similar to the 10 opening 14 of the outer link except that it is slightly longer at normal temperatures.

The difference in lengths between the exterior of the inner link and the interior of the outer link 15 is such that the outer link may, when expanded by heating it sufficiently, be placed on the inner link and shrunk tightly thereover, which is done when the two sections are assembled. When so assembled, which may be accomplished with relative ease, the two parts are firmly bound together 20 and provide a strong and rigid structure. To improve the union between the two their contacting surfaces are machined as accurately as is possible before the two are assembled.

25 Like the outer link, the inner link is provided with an opening 10 which constitutes the window within which the roll assembly is mounted. This opening, however, is dissimilar from the opening 14 in that it is made substantially rectangular in 30 shape so that its end portions are provided with semicircular arches which increase the strength of the housings and adapt them to rigidly withstand the forces exerted upon them when a piece of metal is passed between the rolls, or in other 35 words, minimize the amount of bending which such forces tend to produce.

The chief advantages flowing from this invention as mentioned hereinbefore are that it makes it possible to produce with equal casting difficulties a roll housing having substantially twice the 40 size of an integrally cast housing. In addition to this, by reason of the more efficient utilization of the metal in the castings, smaller castings may be used for a given sized mill which makes for 45 better castings, for, as is well known, the gas pockets, blowholes, internal strains and such other imperfections which are encountered in the making of castings, are of less consequence the smaller the cross section of the castings, and these 50 in tremendously large castings become of real importance.

In addition to the above-mentioned manufacturing advantages of the invention, a roll housing constructed in accordance herewith has the further advantage that it is capable of withstanding greater stretching forces with a lesser amount of stretching at the housing window and deflection of the housing side walls, than is produced in 55 housings which are made in a single solid piece. This is attributed principally to two factors, first, the fact that the planes of contact between the housing sections at the sides of the housing are such that they permit a slip to occur between the inner and outer links when subjected to endwise 60 stresses, which, in view of such stress in a mill being applied at the center of the mill, adapts the outer link to carry a greater portion of the stretch-resisting load than is the case of a unitary structure. The other factor which contributes to the 65 above result is the fact that the outer link is shrunk upon the inner link, thereby causing the inner one to be initially subjected to compression and the outer link to tension, which aids in effecting the above-mentioned distribution of stresses.

70 By way of illustrating this point, reference will

be had to Figs. 4 and 5 of the drawings. According to an accepted diagnosis of the conditions obtaining in a roll housing when rolling is taking place, and which has been illustrated in various ways, the stretching produced in integrally cast housings occurs substantially in the proportions indicated by the dotted lines 21 and 22, that is, the maximum amount of stretching occurs adjacent the walls of the housing window and gradually diminishes towards the outer wall of the housing. The concentration of stress on the inner fibers of the housing wall or post of an integral housing is due to the beam action of the top and bottom members. This results in an unequal loading at the junction of post and beam. In the articulated housing this action is still present, though in different degree, but the initial compression of the inner housing compensates for this inequality so as to more nearly approach the conditions of a member in pure tension. In this latter form of housing the stretching will be actually in substantially the ratio shown by the lines 21a and 22a in Fig. 5.

In accordance with the invention, as illustrated diagrammatically in Fig. 5, due to the housing being in two parts and having sliding vertical surfaces therebetween, the force distributions resulting from the rolling forces imposed on the housing do not follow the same distribution as in a housing which is cast in a single section, as indicated in Fig. 4. As shown, by reason of the links 1 and 2 having circular contacting surfaces at their two ends, the rolling forces are transmitted to the outer link along approximately radial lines substantially perpendicular to the 110 periphery of such end surfaces, and by reason of the vertical contacting surfaces of the two links lying in vertical planes, relative movement between them is permitted, causing the outer link to be subjected to a substantially uniform tensile strain over its length inasmuch as when stretched it slides with respect to the inner link. Consequently, the outer link is more effectively utilized to withstand the stretching stresses exerted upon the housing than is that portion of 120 a unitary housing. Hence, while the total amount of stretching taking place in the housing may be the same as that which takes place in a housing of similar size cast in one section for a given stress, the average amount of stretching, 125 and particularly the amount of stretching at the window opening in the housing, is materially reduced as well as the deflection of the side portion of the housing. The chief advantages of this feature are that the stretching which interferes with the rolling operation of the mill is minimized, and accordingly for a given size of housing a lesser amount of material may be used in making a casting to comply with a given stretching tolerance.

130 According to the provisions of the patent statutes, I have explained the principle and mode of operation of my invention, and have illustrated and described what I now consider to represent its best embodiment. However, I desire to have it understood that, within the scope of the appended claims, the invention may be practiced otherwise than as specifically illustrated and described.

135 I claim:

140 1. The method of making a roll housing for a metal rolling mill comprising forming an outer housing section having an opening in the center thereof, forming an inner housing section having a peripheral contour of the same shape but 145

150

slightly larger than the opening in the outer section, and heating and shrinking said outer section upon said inner section.

2. The method of making a roll housing for a metal rolling mill comprising forming an outer housing section having an opening in the center thereof, forming an inner housing section having a peripheral contour of the same shape but slightly larger than the opening in the outer section, and assembling the two so as to produce an initial tension in the outer section and an initial compression in the inner section.

3. The method of making a roll housing for a metal rolling mill comprising forming an outer housing section with an opening in the center thereof, the ends of which have the curvature of a circle and the sides of which are parallel to each other and extend tangential to the curvature of the ends, forming an inner housing section with an outer peripheral contour similar to but slightly larger than the opening in the outer section, and heating and shrinking said outer section upon the inner section.

4. A roll housing for a metal rolling mill comprising an outer section having an oblong opening in its center, and an inner section provided with a bearing window in its interior and a peripheral contour corresponding to the opening in said outer section with said outer section shrunk upon the inner section in a manner to form a substantially unitary structure.

5. A roll housing for a metal rolling mill comprising a pair of link-like cast sections mounted with one shrunk upon the other, the inner of said sections having a roll window in its center and an exterior surface which is parallel at the sides and round at the ends, and the outer section having an opening in its center which is similar in shape but slightly shorter under normal conditions than the exterior of the inner link whereby the inner link is subjected to compression and the outer link to tension when assembled.
